MOP WRINGER WITH PRESSURE ROLLERS
AND CARRYING BAIL

Edward Wurdeman, Minneapolis, Minn.

Application January 1, 1945, Serial No. 570,847

1 Claim. (Cl. 15—262)

1

My invention relates to improvements in mop wringers.

An object of this invention is to provide a mop wringer in which a mop may be placed, the wringer operated to produce a squeezing action, the mop pulled to wring the same and the wringer carried from place to place by the operator while he stands in an upright natural position and without having to stoop.

A further object of the invention is to provide a mop wringer in which the squeezing action is produced by a downward pressure by the operator with one of his hands, while at the same time he pulls the mop directly toward himself with his other hand to wring the mop.

A still further object of the invention is to provide a mop wringer in which the force applied to produce a squeezing action on the mop holds the wringer from moving while pulling a mop to wring the same.

Another object of the invention is to provide a mop wringer with a handle by which it may be carried and which handle is automatically moved into and out of the way during the wringing of a mop and automatically returned to its normal position at the completion of the wringing operation.

Still another object of the invention is to provide a mop wringer that is sanitary, light in weight, does not cause excessive wear on a mop during the wringing thereof and will not catch the strings of a mop.

Another object of the invention is to provide a mop wringer having means for removably holding a pail for catching water wrung from a mop, for carrying the pail therewith when it is being moved from place to place and wherein the pail may be removed from the mop wringer and emptied.

Other objects of the invention will be apparent from the following description, reference being had to the accompanying drawings.

To the above end, generally stated, the invention consists of the novel devices and combination of devices hereinafter described and defined in the claim.

In the accompanying drawings, which illustrate the invention, like characters indicate like parts throughout the several views.

Referring to the drawings:

Fig. 1 is a front elevation of the improved mop wringer; and

Fig. 2 is a central vertical section taken on the line 2—2 of Fig. 1, and also showing some parts in different positions by means of broken lines.

The numeral 3 indicates a base or platform on which is rigidly secured an upright frame 4. This frame 4 includes a pair of posts 5 connected at their upper end portions by a cross-tie bar 6.

2

These posts 5 are further connected by a pair of crossed braces 7. The frame 4 also includes an oblique brace 8 for each post 5. These braces 8 extend from the front of the platform 3 to the upper ends of the posts 5.

The mop wringer includes a pair of co-operating wringing rolls 9 and 10, the former being stationary and the latter being movable. The roll 9 is journaled on the outer end portions of a pair of substantially horizontally disposed side bars 11. These side bars 11 are rigidly secured to the posts 5 and the braces 8 and, in a broad sense, said side bars form a part of the frame 4. The side bars 11 are further secured to the posts 5 by oblique braces 8'.

The roll 10 is journaled on the intermediate portions of a pair of arms 12 pivoted, at their inner ends to the posts 5 for vertical swinging movement over the side bars 11. When the arms 12 are lowered, they position the movable roll 10 on the stationary roll 9. Said arms 12, when raised, carry the movable roll 10 upwardly and rearwardly from the stationary roll 9. During the raising and lowering of the roll 10, its longitudinal axis moves on the arc of a circle that passes substantially through the longitudinal axis of the stationary roll 9.

The arms 12 are manually raised and lowered by means of a pair of levers 13 pivoted to the upper end portions of the posts 5 for vertical swinging movement. These levers 13 are rigidly connected by a cross-tie bar 13'. A horizontal handle bar 14 by which the levers 13 are manipulated, is secured to the levers 13 at their outer end portions. Upright links 15 connect the levers 13 to the arms 12. These links 15, at their upper ends, are pivoted to the levers 13, at their intermediate portions and said links at their lower ends are pivoted to arms 12 at their outer ends.

The roll 9 is journaled to the arms 12 relatively near their outer ends.

The levers 13 are in substantially a horizontal position when the roll 10 is in an operative position on the roll 9. This arrangement of the levers 13 positions the handle bar 14 where the same may be grasped by the operator with one of his hands, without having to stoop, and pressed downwardly thereon to force the upper roll 10 onto a mop, extending over the roll 9, and thereby produce a squeezing action on the mop. At this same time the operator, with his other hand, pulls the mop toward himself to draw the mop between the rolls 9 and 10 and thereby wring the same.

All movements of the operator in placing a mop transversely over the lower roll 9, in manipulating the handle bar 14 to bring the roll 10 into an operative position relative to the lower roll 9 and in pulling the mop between the rolls 9 and 10 to wring the same are all performed while the

operator is standing in an upright position and with little effort.

A pail *x*, indicated by broken lines in Fig. 1, is placed on the base *3* to catch water wrung from a mop by the rolls *9* and *10*. The pail *x* may be placed on the platform or removed therefrom without moving any part of the wringer.

A splash guard *16* is secured to the frame *4* to intercept water thrown from the mop or wrung therefrom and directs the same into the pail *x*. An upright bail-like handle *17* is provided for use in carrying the mop wringer from place to place. The side members of the handle *17* are pivoted at their lower ends to the oblique braces *8*. The splash guard *16* is shown by full lines in Fig. 1 and by broken lines in Fig. 2. A pair of coiled springs *18* yieldingly hold the handle *17* with its horizontal member, which extends in front of the links *15*, pulled against said links. These springs *18* are attached to the side members of the handle *17* and are anchored to the posts *5*.

When the levers *13* are moved by the handle bar *14* to lower the roll *10*, the links *15* push the handle *17* forwardly therewith. During the return movement of the movable roll *10* by the levers *13*, the springs *18* return the handle *17* and keep the same in engagement with the links *15*.

The handle *17* also performs another important function which is, it yieldingly holds the arms *12* and the levers *13* in their raised positions as shown in Fig. 2. When the arms *12* and the levers *13* are raised, they are out of the way of the handle *17* when used to carry the mop wringer.

The length of the roll *9* is such as to permit a mop to be pulled therebetween without coming in contact with the frame and thus prevents excessive wear thereon.

As heretofore stated, manual pressure on the handle bar *14* to produce squeezing action on a mop by the rolls *9* and *10* holds the mop wringer from moving on the floor while the mop is being pulled between said rolls to wring the same.

From what has been said, it will be understood that the mop wringer described is capable of modifications as to details of construction and arrangement within the scope of the invention herein described and claimed.

What I claim is:

A mop wringer and frame comprising a pail platform, an upright frame on the platform, a fixed lower roll journaled on the frame, a pair of arms pivoted to the frame, an upper roll journaled on the arms for cooperation with the lower roll, a handle bar having a pair of arms pivoted to the frame above the first noted pair of arms, pivoted links connecting the first noted arms to the arms of the handle bar, and a carrying bail for said mop wringer having side members connected by a horizontal member pivoted to the frame, and springs anchored to the frame and attached to the side members of the carrying bail, said springs yieldingly holding said horizontal member against the links and said links in turn holding the pairs of arms, the upper roll in raised inoperative position and the bail in its operative position, when the upper roll is in wringing position over the lower roll, said pairs of arms being substantially horizontally disposed and said links being substantially vertically disposed between the pairs of arms.
